K. H. V. VON PORAT

FURNACE FOR PULVEROUS FUEL

1,462,310

UNITED STATES PATENT OFFICE.

KARL HJALMAR VILHELM VON PORAT, OF STOCKHOLM, SWEDEN, ASSIGNOR TO MOTALA VERKSTADS NYA AKTIEBOLAG, OF MOTALA VERKSTAD, SWEDEN, A CORPORATION.

FURNACE FOR PULVEROUS FUEL.

Application filed November 4, 1919. Serial No. 335,629.

To all whom it may concern:

Be it known that I, KARL HJALMAR VILHELM VON PORAT, engineer, subject of the King of Sweden, residing at Västra Trädgårdsgatan 4, Stockholm, Sweden, have invented certain new and useful Improvements in Furnaces for Pulverous Fuel, of which the following is a specification.

The present invention relates to boiler furnaces burning pulverulent fuel, particularly for locomotives, in which the fuel together with a gaseous medium, such as air, is forced below an arch of refractory material so that the mixture of air and fuel is caused to pass along the under side of the arch and then along the upper side thereof, before it escapes through the fire tubes in the boiler.

The invention has for its purpose to provide a simple and strong construction, which is adapted to burn all the different kinds of pulverulent fuels; both the easily ignited kinds, such as fat pit coals rich in gases, as well as those not readily ignited, such as poor pit coals or coarse grained peat powder.

A practical embodiment of the invention is shown in the accompanying drawings in which:

Fig. 1 shows the furnace in vertical section. Fig. 2 is a section on the lines G—H and I—K of Fig. 1. The left half of Fig. 3 is a section on the line A—B and the right half is a section on the line C—D of Fig. 1. Fig. 4 is a section on the line E—F of Fig. 1, and Fig. 5 shows a detail on a larger scale.

1 indicates a plate mantle and consists of a crown sheet, side sheets and a flue sheet, which form the top and side walls of the fire box or furnace and the rear end of a boiler. 2. From the flue sheet, to which the rear ends of the fire tubes, passing through the water in the boiler, are attached in usual way, there projects upwardly in an inclined position an arch 3 of refractory material. In Figs. 3, 4 and 5 the means for supporting the arch is shown in detail. This means consists of screw bolts 15 which are screwed into the side sheets at opposite sides, and iron beams 16, resting on these screw bolts. The edges of the arch 3 are formed of hook-shaped bricks which engage the beams 16 and bolts 15 in order to support the arch.

The spaces between these bricks and the bolts 15 and beams 16 are filled with refractory material. The lower part of the front wall of the flue sheet, that is, the part which is located below the arch, is coated with a wall of refractory material 12.

The bottom of the furnace chamber as well as the lower part of its side walls also consists of refractory material, except that part of the bottom which is formed by the grate 6, which is arranged in the front part of the furnace below the arch. The bottom part of refractory material behind the grate is indicated by 4, and the lateral walls confining the lower part of the furnace chamber are indicated by 28. A tube 5 for supplying the pulverulent fuel opens into a channel 18 in the bottom part 4. The fuel is impelled through and from the tube 5 in the combustion chamber by the draught in the furnace, or it may be blown into the chamber with a gaseous medium such as air. The arrangement is such that at least the inner part of the channel 18 is located below the arch 3. Although the bottom part 4 is inclined, it has a relatively great extension horizontally at that point where the channel 18 is located, so that this latter may be relatively long. This channel forms a primary mixing and heating channel for the fuel.

As will be clearly seen from Fig. 3, the brick-work walls 28 which constitute the sides of the lower part of the combustion chamber, do not extend to the arch 3, but the upper part of the chamber between the arch and the grate is bounded laterally by the side and crown sheets 1, which is in contact with water and thus cooled. The channel 18, in which the tube 5 projects, opens into the said lower part of the combustion chamber that is between the brick-work walls 28. It should be noted that the arrangement is such that the space between the brick-work walls 28 is much narrower than the upper part of the chamber below the arch 3, and between the side sheets. Preferably, the said lower part should be only about one-half as wide as said upper part. As the channel 18 is horizontal, the mixture of air and fuel flows forwardly to the front part of the combustion chamber below the arch and between the brick-work walls 28, and then rearwardly along the arch between the

water-cooled side sheets below the arch, after which it escapes upwardly at the rear end of the arch and thence flows along the upper side of the arch into the fire tubes.

5 The grate 6 is composed of two halves, which can swing downwardly around the pivots 7 for emptying the slag formed in the furnace. The free ends of the grate halves are held in their upper working position, shown in the drawing, by means of the devices which serve to swing the same.

10 The space below the grate is enclosed by a casing 29. This casing is provided with a damper or door 34, which in turn is preferably provided with air inlet openings, controllable from the cab of the locomotive.

15 In the embodiment shown, the front grate half can be operated from the cab of the locomotive. Said grate half is connected by means of a link 30 with an arm 31 on a shaft 32 which is mounted in the casing 29 and which is provided outside of the casing with an arm 33, which, by means of a suitable link and lever device is connected with

20 a handle conveniently accessible from the cab of the locomotive. The rear grate half is held in its upper position by a connection 35 which is accessible from the underside of the casing and which, by means of a pin or the like, is secured to a projection 36 on the bottom of the casing.

25 In the rear of the furnace below the usual firing opening 23, there are air inlet channels 10 which are enclosed by brick-work 35 and which are arranged in such a way that the air flowing into the same passes forwardly into the chamber below the arch 3. The upper confining wall of said air channels is formed by a cross member 11. The 30 air comes into the channels 10 through an inlet 8, which is attached to the underside of the furnace and which is provided with a door or damper 17. This damper is preferably arranged so as to be controlled by devices accessible from the cab of the locomotive.

35 When using easily ignitable fuel, all or the greater part of the combustion air is supplied through the grate 6, but a part 50 may enter through the inlet 8 and channels 10.

40 When using fuel that is not readily ignited, care should be taken not to supply too much air through the grate 6, as too much air excessively reduces the temperature, so that the ignition and the combustion will be incomplete or fail. Therefore, the greatest part of the combustion air, under these circumstances, is admitted through the inlets 45 8 and 10.

45 The furnace can be fired up with wood and coal in the usual manner and about as rapidly as is usual in furnaces fired with coal. When firing with pulverulent fuel it 50 is not necessary in most cases to have a

fire on the grate, but this can be completely empty. If, on the contrary, the fuel is very difficult to ignite, a very small quantity of coal or wood is used on the grate in order to obtain a better ignition. In this case, however, the layer of coal or wood ought to be so thin and sparse that some part of the air passes through it without combustion, to serve as combustion air for igniting the pulverulent fuel.

75 The casing 29 below the grate, as well as the inlet 8 through which air is supplied to the air channels 10, serves to receive the ashes.

80 The member 11 above the air channels 10 serves partly to prevent wood or coal from falling down into the inlet 8 and forming a fire in this inlet, which fire would soon injure the inlet 8, and partly to guide the air from the channels 10 forwardly in a direction away from the flue sheet 1, so that the air will not cool the flue sheet but will enter the combustion channel and support combustion of the fuel therein.

85 In order to obtain a better heat insulation for the lower part of the combustion chamber, which part is confined by the brick-work 28, the space 13 between the brick-work 12 and 28, and the side sheets enclosing said brick-work, is filled up with ashes.

90 An annular opening is left around the pipe 5 where it enters the channel 18, so that a small amount of air may pass therethrough from the inlet 26, to hold the fuel in suspense in the channel 18 or to serve for the combustion of the fuel when only a 95 very small quantity is used.

100 It is thus to be observed that, according to the present invention, there are three different air inlets arranged in a peculiar manner so that means are provided whereby the air supply can be controlled according to the quality of the fuel being used. Through two of the air inlets, namely the channels 18 and 10, the air flows forwardly into the combustion chamber below the arch 3 while the air flowing through the grate openings, which form the third air inlet, passes upwardly into the combustion chamber.

105 The channel 18 which admits both air and fuel, is located between the two other air inlets both horizontally and vertically. The upper surface of the middle part of the furnace bottom, which surface is located behind the grate but below the arch 3, is inclined so as to converge rearwardly with the under surface of arch 3. Hence a view of the whole grate 6 can be obtained through the firing opening 23, and the grate may also be cleaned by the use of a straight tool.

115 What I claim is:

120 1. In a furnace for different kinds of fuel, the combination of a combustion chamber, a firing opening in the rear end wall of said chamber, an arch dividing said chamber 125

- into an upper and a lower compartment communicating with each other at the rear part of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part of the upper compartment and then forwardly along the upper side of the arch before escaping from the chamber.
2. In a furnace for different kinds of fuel, the combination of a combustion chamber, a firing opening in the rear end wall of said chamber, an arch dividing said chamber into an upper and a lower compartment communicating with each other at the rear part of the chamber, a grate in the front part of the bottom of the chamber, said arch projecting rearwardly beyond the said grate, the rear and lateral parts of the bottom of the chamber being composed of refractory material, and means for causing one kind of fuel to flow from the rear part of the chamber first forwardly to the front end of the lower compartment, then rearwardly to the rear part of the upper compartment and then forwardly along the upper side of the arch before escaping from the chamber.
3. In a furnace for different kinds of fuel, the combination of a combustion chamber, a firing opening in the rear end wall of said chamber, an arch dividing said chamber into an upper and a lower compartment communicating with each other at the rear part of the chamber, a grate in the front part of the bottom of the chamber, said arch projecting rearwardly beyond the said grate, the rear part of the bottom of the chamber being composed of refractory material, means for causing one kind of fuel to flow from the rear part of the chamber first forwardly to the front end of the lower compartment, then rearwardly to the rear part of the upper compartment and then forwardly along the upper side of the arch before escaping from the chamber, and a horizontal channel forming an air inlet arranged in the rear part of the bottom of the chamber composed of refractory material, said channel being partially located below the said arch.
4. In a furnace for different kinds of fuel, the combination of a combustion chamber, a firing opening in the rear end wall of said chamber, an arch dividing said chamber into an upper and a lower compartment communicating with each other at the rear part of the chamber, a grate in the front part of the bottom of the chamber, said arch projecting outwardly beyond the said grate, the rear part of the bottom of the chamber being composed of refractory material, and means for causing one kind of fuel to flow from the rear part of the chamber first forwardly to the front end of the lower compartment, then rearwardly to the rear part of the upper compartment and then forwardly along the upper side of the arch before escaping from the chamber, the part of the bottom of the chamber composed of refractory material being inclined upwardly and rearwardly from the rear end of the grate so that the whole grate will be visible through the said firing opening.
5. In a furnace for different kinds of fuel, the combination of a combustion chamber, a firing opening in the rear end wall of said chamber, an arch dividing said chamber into an upper and a lower compartment communicating with each other at the rear part of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment, then rearwardly to the rear part of the upper compartment and then forwardly along the upper side of the arch before escaping from the chamber, the upper part of the lateral walls of the chamber between the grate and the arch being composed of cooled plates and the lower part of said lateral walls being composed of refractory material.
6. In a furnace for different kinds of fuel, the combination of a combustion chamber, a firing opening in the rear end wall of said chamber, an arch dividing said chamber into an upper and a lower compartment communicating with each other at the rear part of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part of the upper compartment and then forwardly along the upper side of the arch before escaping from the chamber, the upper part of the lateral walls of the chamber between the grate and the arch being composed of cooled plates and the lower part of said lateral walls being composed of refractory material, the lower part of said walls being closer together than the upper part thereof.
7. In a furnace for different kinds of fuel, the combination of a combustion chamber, a firing opening in the rear end wall of said chamber, an arch dividing said chamber into an upper and a lower compartment communicating with each other at the rear part of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment, then rearwardly to the rear part of the upper compartment and then forwardly along the upper side of the arch before escaping from the chamber, the part of the bottom of the chamber composed of refractory material being inclined upwardly and rearwardly from the rear end of the grate so that the whole grate will be visible through the said firing opening.

- the bottom of the chamber, said arch projecting rearwardly beyond the said grate, the rear part of the bottom of the chamber being composed of refractory material, means 5 for causing one kind of fuel to flow from the rear part of the chamber first forwardly to the front end of the lower compartment then rearwardly to the rear part of the upper compartment and then forwardly along 10 the upper side of the arch before escaping from the chamber, and an air inlet being located in the rear part of the said bottom whereby the air flowing therethrough flows forwardly into the chamber.
- 15 8. In a furnace for different kinds of fuel, the combination of a combustion chamber, a firing opening in the rear end wall of said chamber, an arch dividing said chamber into an upper and a lower compartment communicating with each other at the rear part 15 of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part 20 of the upper compartment and then forwardly along the upper side of the arch before escaping from the chamber, said grate being pivoted to swing on a horizontal axis.
- 25 9. In a furnace for pulverulent fuel, the combination of a combustion chamber, a firing opening in the rear end wall of said chamber, an arch dividing said chamber into an upper and a lower compartment communicating with each other at the rear part 25 of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part 30 of the upper compartment and then forwardly along the upper side of the arch before escaping from the chamber, and a plurality of air inlets being located in the rear part of said bottom of the chamber composed of refractory material, certain of said inlets being positioned above the others.
- 35 10. In a furnace for different kinds of fuel, the combination of a combustion chamber, a firing opening in the rear end wall of said chamber, an arch dividing said chamber into an upper and a lower compartment communicating with each other at the rear part 35 of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part 40 of the upper compartment and then forwardly along the upper side of the arch before escaping from the chamber, and a horizontal channel forming an air inlet arranged in the rear part of the bottom of the chamber, said channel being partially located below the said arch.
- 45 11. In a furnace for different kinds of fuel, the combination of a combustion chamber, a firing opening in the rear end wall of said chamber, an arch dividing said chamber into an upper and a lower compartment communicating with each other at the rear part 45 of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part 50 of the upper compartment and then forwardly along the upper side of the arch before escaping from the chamber, said grate being pivoted to swing on a horizontal axis.
- 55 12. In a furnace for different kinds of fuel, the combination of a combustion chamber, a firing opening in the rear end wall of said chamber, an arch dividing said chamber into an upper and a lower compartment communicating with each other at the rear part 55 of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part of the upper compartment and then forwardly along the upper side of the arch before escaping from the chamber, said grate being divided into a plurality of sections adapted to swing on a horizontal axis.
- 60 13. In a furnace for different kinds of fuel, the combination of a combustion chamber, a firing opening in the rear end wall of said chamber, an arch dividing said chamber into an upper and a lower compartment communicating with each other at the rear part 60 of the chamber, a grate in the front part of the bottom of the chamber, said arch projecting rearwardly beyond the said grate, the rear part of the bottom of the chamber being composed of refractory material, and means for causing one kind of fuel to flow from the rear part of the chamber first forwardly to the front end of the lower compartment then rearwardly to the rear part of the upper compartment and then forwardly along the upper side of the arch before escaping from the chamber, the arch and the part of the bottom of the chamber composed of refractory material below the arch converging rearwardly.
